UNITED STATES PATENT OFFICE.

NEWTON N. READ, OF ALBUQUERQUE, NEW MEXICO.

OINTMENT.

1,312,047.

Specification of Letters Patent. Patented Aug. 5, 1919.

No Drawing.

Application filed October 31, 1916. Serial No. 123,775.

To all whom it may concern:

Be it known that I, NEWTON N. READ, a citizen of the United States, residing at Albuquerque, county of Bernalillo, and State 5 of New Mexico, have invented certain new and useful Improvements in Ointments, of which the following is a specification.

My invention relates to an ointment for external application, especially adapted for 10 the treatment of tuberculosis and it consists in the following ingredients combined in the proportions stated viz.

15.	Castile soap	6	parts
	Rosin	4	"
	Beeswax	4	"
	Spirits of camphor	3	"
	Tincture of capsicum	2	"
	Oil of hemlock	1	"

20 In preparing the ointment the solid ingredients such as the soap, rosin and the beeswax should first be melted together over a slow fire until thoroughly mixed. This mixture should then be allowed to cool 25 slightly and then add thereto the liquids such as the spirits of camphor, tincture of capsicum and the oil of hemlock. The whole mass should then again be heated to insure a thorough mixture that will not 30 separate and which remains perfectly effectual indefinitely. While in this heated condition the mass should constantly be kept in a state of agitation which should be continued until cool.

35 The resultant salve is applied to the chest, side or back as the case may require and covered with a shield or two or more thicknesses of cloth to protect the outer clothing from the ointment and the pus.

40 From actual experience it has been found that after the patient has had the ointment applied to the diseased part for about forty-eight hours there will appear on the

skin directly over the affected lung or part a facsimile of the diseased lung. There also 45 will be found a thick creamy pus which becomes more profuse as the ulcerated surface in the lung becomes more and more stimulated and as the discharge becomes more profuse the tuberculosis bacilli be- 50 come less numerous in the specimen of sputum examined under the microscope. When the germs decrease in number to a very perceptible extent the lungs, on examination are found to be healing, the rales disappear 55 and the several methods of examinations used show that the lungs are clearing and the general symptoms of the patient greatly improved. Patients under this form of treatment are immediately relieved from 60 pleuritic pains and as soon as the healing process is set up they are also free from the dangers of hemorrhages from the lungs.

The application of the ointment should be at least once daily, thoroughly cleansing 65 the surface over the diseased lung before another application.

What I claim is:

1. A composition consisting of castile soap, rosin, beeswax, spirits of camphor, 70 tincture of capsicum and oil of hemlock in about the proportions named and for the purpose specified.

2. A composition consisting of six parts castile soap, four parts rosin, four parts 75 beeswax, three parts spirits of camphor, two parts tincture of capsicum and one part oil of hemlock substantially as described and for the purpose specified.

In testimony whereof I affix my signature 80 in presence of two witnesses.

NEWTON N. READ.
